UNITED STATES PATENT OFFICE

115,041

DESIGN FOR A FISHING FLOAT

Earl Ray Griffith, Beaumont, Tex., assignor of one-half to Seldon B. Small, Beaumont, Tex.

Application March 23, 1939, Serial No. 83,799

Term of patent 7 years

To all whom it may concern:

Be it known that I, Earl Ray Griffith, a citizen of the United States, residing at Beaumont, in the county of Jefferson and State of Texas, have invented a new, original, and ornamental Design for a Fishing Float, of which the following is a specification, reference being had to the accompanying drawing, forming part thereof.

I claim:

The ornamental design for a fishing float, as shown.

EARL RAY GRIFFITH.
